UNITED STATES PATENT OFFICE

2,506,459

IRONING BOARD

William Lampiris, Milwaukee, Wis., assignor to
Geuder, Paeschke & Frey Co., Milwaukee, Wis.,
a corporation of Wisconsin

Application April 6, 1946, Serial No. 660,163

3 Claims. (Cl. 219—19)

1

This invention relates to improvements in ironing boards and particularly to heated metallic boards.

Metallic ironing boards which are heated from beneath the top of the board prevent the accumulation in the pad and cover set of moisture and permit a more rapid and even ironing of the material being pressed. Heretofore ironing boards of this type did not have replaceable heating elements nor was there provision for selecting various degrees of heat. Thus their useful life was shortened and their adaptability for use with material of varying characteristics limited.

It is an object of this invention, therefore, to provide a heated metallic ironing board in which the heat supplied to the ironing surface may be selectively varied.

Another object of the invention is to provide a heated metallic ironing board in which the heating elements are readily replaceable.

A further object of the invention is to provide a metallic heated ironing board which is simple in design and economical to manufacture.

These objects are accomplished by providing an ironing board which has a metallic top supported on a reinforcing member having longitudinally extending and spaced channels which terminate with open ends spaced from the head of the ironing board. A harness formed of a pair or more of wires or heating elements covered with heat resistant insulation such as asbestos has elongated finger-like loops which are inserted into the respective channels through the open ends thereof with the terminal ends exposed. These terminal ends are connected with the source of power through a selector switch which selectively connects one of the elements in series or two or more of the elements of the harness in parallel with the source or disconnects all of the elements. Thus the heat delivered to the board may be selectively controlled. The open ends of the channels are enclosed by a pan which is detachably secured to the bottom of the ironing board. This pan carries the selector switch, a connecting cord by which the unit is connected with the source of power, and a plug outlet for an electric sad iron. The pan is detachably secured to the underside of the ironing board and when removed the harness is withdrawn with it. Thereupon the terminal connections are all exposed for ready attaching of a new harness. To install the unit the finger-like loops are slid into their respective channels through the open ends and the enclosure pan attached in place.

The novel features, which are considered char-

2

acteristic of the invention, are set forth with particularity in the appended claims. The invention itself, however, both as to its organization and its method of operation, together with additional objects and advantages thereof, will best be understood from the following description of a specific embodiment when read in connection with the accompanying drawing, in which:

Figure 1 is a top plan view of a metallic ironing board embodying the present invention, part of the top being broken away for the sake of illustration;

Figure 2 is a side elevation of the ironing board viewed in Figure 1;

Figure 3 is an end elevation of the head of the ironing board of Figure 1;

Figure 4 is a bottom plan view of the ironing board viewed in Figure 1;

Figure 5 is a top plan view of the enclosure pan comprising a part of the present ironing board removed therefrom;

Figure 6 is a sectional view taken on the line 6—6 of Figure 1;

Figure 7 is a sectional view taken on the line 7—7 of Figure 1;

Figure 8 is a plan view of the harness of resistance wire constituting the heating elements for the ironing board of Figure 1;

Figure 9 is a sectional view taken on the line 9—9 of Figure 6; and

Figure 10 is a schematic wiring diagram of the circuits utilized in this invention.

Referring to the drawings by reference numbers, the ironing board comprises an imperforate sheet metal top 10 which has a depending marginal edge 40. The top 10 is shaped like the conventional ironing board, having a head to the left and a toe to the right, as viewed in Figures 1, 2 and 4. Secured to the undersurface of the top 10 is a reinforcing member 11 formed or corrugated with a series of longitudinally extending inverted channels 12 spaced by longitudinally extending channels or troughs 13. The member 11 conforms in shape substantially with the top 10 except that it terminates along a line spaced from the head of the top 10 to provide openings to the channels 12 and space for the switch and outlet. The upper surfaces of the inverted channels 12 rest against and, as indicated at S, are spot-welded to the undersurface of the top 10, to form a rigid unit. The bottom of the marginal edge 40 of the top 10 may be provided with a protective bead. Cross-members 14 and 15, to which the folding legs of well-known design may be secured, extend from side to side of the bottom of

the board and are welded to the depending edge 40 and the bottoms of the channels 13.

As previously pointed out, the reinforcing member 11 does not extend to the head of the table 10. It terminates along a line which is coincident with the section line 6—6 of Figure 1 to provide five of the channels 13 with open ends through which the electrical heating elements are inserted. The heating elements comprise two lengths of Nichrome or other wire insulated with an asbestos cover. One length is designated *a* and the other *b*. The lengths are positioned side by side with their terminal ends adjacent each other. There is then formed in each wire a series of five loops or fingers 17 which are tied at the open end as indicated at 18 or held by clips or other fastening means to form a harness 16 as shown in Figure 8. The lengths of the loops or fingers 17 correspond substantially with the lengths of the respective channels 13 into which a respective loop is inserted. To install the harness it is only necessary to start each loop in the opening of its respective channel and then slide the whole harness into the position shown in Figure 1. In order to protect the wire from chafing at the openings of the channels 13, the edges of the channels at such openings may be rounded off or there may be provided an end member 19 provided with a series of apertures 20 located in alinement with the opening of each of the five respective channels 13. In forming the apertures 20, they are so pierced as to provide a turned-in bead 21 (illustrated in Figure 9) which provides a smooth and broad surface. The end member 19 may be spot-welded or otherwise secured in place across the ends of the channels.

An enclosure pan or removable cover plate 22 holds the heat selector switch 30, the sad-iron outlet 31 and the electric cord 32 for connecting the whole unit to the source of electric power. It also closes the openings to the channels 13 and cooperates with the underside of the ironing board to provide space for the bodies of such switch and outlet and for the various terminals and wire connections including portion of the heating elements between the fingers 17. The pan 22 has a circular shaped edge to conform with the head of the ironing board. This edge has an upstanding rim 23 which fits within the depending edge 40. The rim 23 is provided with tabs 24 which engage the underside of the top to position the pan. Screws 25 hold the tabs to the edge 40 to detachably hold the pan. The pan 22 also has a straight edge provided with projections 26 which, in the assembled condition, are contained between the inverted channels 12 and rest on top of the cross member 15 to hold that end of the pan in position. The bottom of the pan 22 comprises walls 27 and 28 which slope upwardly and outwardly from the flat central portion of the bottom.

The slope of wall 27 urges the elastic draw edge of any pad and cover set upwardly to prevent it from interfering with the operating member of the switch 30 and the openings to the sad-iron outlet 31.

The selector switch 30 is mounted within the pan 22 to the left of center, as viewed in Figure 3. Its operating lever projects outwardly through the wall 27 so that it may be easily accessible at the head of the ironing board. The switch 30 is a double pole two-throw switch of customary construction, but only three of the terminals are utilized as will be seen from the schematic draw-

ing of Figure 10. An outlet 31 of customary design is positioned within the pan 22 on the opposite side from the switch 30. There is an opening in the wall 27 which receives the face of the outlet 31 so that the plug of the cord of an electric sad iron may be readily fitted in the outlet. An electric cord 32 enters the pan from the bottom, and is connected to the terminals of the socket 31. This cord has the usual plug (not shown) which permits it to be connected with a source of electric power.

As shown in the circuit diagram of Figure 10, one end of wire *a* and wire *b* are each secured to one terminal 33 (see Figure 5) of the outlet 31. The other end of wire *a* is secured to terminal 34 of the switch 30, and the other end of *b* is secured to the adjacent terminal 35. The movable blade of the switch 30 is connected to the other terminal 36 of the outlet 30 and hence through the cord 32 to the other side of the source of supply. The terminal 34 of switch 30 is electrically connected to terminal 37 of switch 30. With these connections and with the cord 32 plugged into a standard source of electrical power, the switch 30 may disconnect both wires, connect wire *a* only, or connect wires *a* and *b* in parallel with the power. When *a* and *b* are both connected, the maximum wattage is consumed and the board is heated at the selected high degree. When the wire *a* only is connected to the source of power, the wattage consumed is decreased and the board is heated at the selected "low" degree. The temperature of the board and any pad or cover set can thus be readily adjusted.

In ironing some material it is preferable to have the board at the high degree while in ironing other material it is more desirable to have the board at the low degree.

The board is provided with a head stand 38 which protects the head of the board and the switch 30 when the board is stored. The stand 38 comprises a bridge member and two legs. The legs extend under the marginal edge 40 and project into respective inverted channels 12 to rest upon and be secured by screws 39 to the top of the cross member 15. The enclosure pan 22 is provided with slots 39 to accommodate the legs of the stand 38 when the pan is secured to the board.

In order to replace the heating elements, it is only necessary to remove the screws 25, permitting the pan 22 to be easily disengaged from the board, and withdraw the pan and the harness 16 from the board as a unit. When withdrawn it is easy to connect a new harness to exposed terminals in the pan. Thereupon the new harness (with pan connected) may be slid into the channels 13, the projections 26 placed into engagement with the cross member 15, and the edge 23 inserted within the margin 40 and secured in place by the screws 25.

Although only one embodiment of the invention is shown and described herein, it will be understood that this application is intended to cover such changes or modifications as come within the spirit of the invention or scope of the following claims.

I claim:

1. An ironing board comprising a flat top having a head at one end, a longitudinally corrugated member secured to the under surface of said top to reinforce said board, said corrugations providing troughs adapted to receive fingers of a removable heater, said member terminating along a line spaced from said head to provide access

to the open ends of said troughs, a removable heater having fingers loosely positioned in said trough, a removable cover plate for the open ends of said troughs and carrying said heater fingers, and auxiliary electrical apparatus also carried by said plate some of which is electrically associated with said heater.

2. An ironing board as claimed in claim 1 in which there is provided a transverse member at the end of said corrugated member, said transverse member having holes in alignment with said open ends of said troughs and accommodating said fingers, said holes being provided with a bead-like margin to facilitate insertion and removal of said heater fingers.

3. An ironing board as claimed in claim 1 in which a cross member extends transversely across said corrugated member and is secured

thereto to brace said board, said removable cover plate having tabs resting on said cross member to aid in holding said plate in position.

WILLIAM LAMPIRIS.
